CLAIM

The ornamental design for a square tube, as shown and described.

DESCRIPTION

FIG. 1 is an isometric view of the square tube;
FIG. 2 is an end view of the square tube of FIG. 1, the
opposing end view being identical thereto; and,
FIG. 3 is a front view of the square tube of FIG. 1, the rear,
top and bottom views being identical thereto.

The square tube is shown with a symbolic break in its length.
The appearance of any portion of the square tube between
the break lines forms no part of the claimed design.
